SLIDE RULE CASE

John W. Pickett, Altadena, Calif., assignor to Pickett & Eckel, Inc., Alhambra, Calif., a corporation of Illinois

Application January 26, 1959, Serial No. 54,312

Term of patent 14 years

(Cl. D87—5)

Fig. 1 is a front elevational view of a slide rule case showing my new design;

Fig. 2 is a side view of Fig. 1;

Fig. 3 is a view similar to Fig. 2 with parts of the case in a different position;

Fig. 4 is a rear elevational view of Fig. 2; and

Fig. 5 is a plan view of Fig. 1.

The clip element shown in broken lines is an optional detail and the portions of a slide rule shown in broken lines are for illustrative purposes.

I claim:

The ornamental design for a slide rule case, substantially as shown and described.
